UNITED STATES PATENT OFFICE.

ERNEST HERSEN, OF NEW YORK, N. Y.

DESIGN FOR A PUZZLE-BOX.

SPECIFICATION forming part of Design No. 26,164, dated October 6, 1896.

Application filed July 30, 1896. Serial No. 601,098. Term of patent 31 years.

To all whom it may concern:

Be it known that I, ERNEST HERSEN, a citizen of the United States, residing at New York, in the county of New York and State of New York, have invented and produced a new and original Design for Puzzle Boxes or Cases, of which the following is a specification, reference being had to the accompanying drawings, forming a part thereof.

10 My new and original design for puzzle boxes or cases is fully disclosed in the following specification, of which the accompanying drawings form a part, in which—

Figure 1 is a plan view of my puzzle box or case, and Fig. 2 a section on the line 2—2 thereof.

The leading feature of my new and original design for puzzle boxes or cases consists of a bottom 5, which is rectangular and square in form and which is provided with suitable side walls 6, and arranged centrally of the bottom thereof is a housing 7, which is square in form and the corners of which point toward the center or middle portion of the sides or 25 side walls 6, and said housing is provided in its opposite sides with openings or passages 9.

Formed in the bottom of the box or easing, at each corner thereof, is a circular cavity or recess 10, and extending from each of said 30 cavities or recesses is a tortuous or winding passage or groove 11, which communicates

with the openings or passages 9 in the side walls of the housing 7. Each of the grooves or passages 11 is exactly of the same form, and by means of this construction and arrangement of parts the configuration of the bottom of the box or easing is rectangular and symmetrical, and the said grooves or passages communicate with the openings or passages 9 in the housing 7 by means of parallel 35 end extensions 12, which also adds to the symmetrical and regular appearance of the bottom portion of the box or easing.

The box or easing is also provided with a transparent cap or cover 13, but this cap or 45 cover is not an essential element of my design and may or may not be employed.

Having fully described my new and original design for puzzle boxes or cases, I claim as new and desire to secure by Letters Patent—

The design for a puzzle box or case, herein shown and described.

In testimony that I claim the foregoing as my invention I have signed my name, in presence of the subscribing witnesses, this 22d day of July, 1896.

ERNEST HERSEN.
